UNITED STATES PATENT OFFICE.

ALBERT A. PAULY AND DAVID HEINSELMAN, OF YOUNGSTOWN, OHIO.

CONCRETE-MOLDING APPARATUS.

No. 839,782.

Specification of Letters Patent.

Patented Dec. 25, 1906.

Application filed May 22, 1906. Serial No. 318,205.

To all whom it may concern:

Be it known that we, ALBERT A. PAULY and DAVID HEINSELMAN, citizens of the United States of America, residing at 5 Youngstown, in the county of Mahoning and State of Ohio, have invented certain new and useful Improvements in Concrete-Molding Apparatus, of which the following is a specification, reference being had therein to the 10 accompanying drawings.

This invention relates to certain new and useful improvements in concrete-molding apparatus particularly designed for molding blocks and plates, such as can be used in constructing sewers, manholes, conduits, meter-boxes, cisterns, and catch-basins.

The invention has for its primary object to provide a mold and apparatus for expeditiously forming blocks and plates from a 15 plastic composition, as concrete.

The present invention is an improvement upon an apparatus disclosed in an application for patent filed January 22, 1906, Serial No. 297,167, allowed May 3, 1906, wherein 20 certain elements, as presses, were utilized for forming rectangular concrete blocks. The apparatus presented in this application is particularly adapted for forming curved plates or blocks having interlocking edges to 25 permit several of said plates or blocks being assembled to form a sewer, conduit, or similar structure.

The detail construction of our improved apparatus will be presently described and 30 then specifically pointed out in the claims.

Referring to the drawings accompanying this application, Figure 1 is a vertical sectional view of one of the presses of our improved apparatus, illustrating a mold positioned beneath said press. Fig. 2 is a cross-sectional view of our improved mold. Fig. 3 is a perspective view of the apparatus. Fig. 4 is a similar view of one of the plates or blocks formed by the apparatus. Fig. 5 is a 35 perspective view of a mold-plate used in connection with the apparatus. Fig. 6 is a fragmentary perspective view of a press. Fig. 7 is a detail elevation of a portion of the press. Fig. 8 is a perspective view of one of the 40 plates or blocks formed by our improved apparatus, and Fig. 9 is a similar view of a 45

50 plates or blocks formed by our improved apparatus, and Fig. 9 is a similar view of a 55

put from a single apparatus. A circular track 1 is employed upon which flat-bottomed cars 2 are moved, these cars carrying our improved molds 3. Each mold consists 60 of a bed-plate 4, having a curved upper face 5, upon which the concrete blocks or plates are formed. The bed-plate 4 is provided with end walls 6 and hinged side walls 7, the latter being secured to the former by clasps 8 65 of a conventional form. The upper edges of the sides 6 and the ends 7 extend above the face of the mold and form a frame to hold the material in position to be acted upon by the die member of the press, the extended sides 70 thus confining the surplus material during the compressing action. The molds 3 are detachably mounted upon the cars 2 in order that they can be removed and molds having bed-plates of different curvature placed 75 thereon.

At diametrical points upon the track 1 we locate presses 9 and 10, and as said presses are identical in construction we deem it only necessary to describe one of said presses. A 80 press comprises four standards 11, supporting a rectangular frame 12 above the track 1. Journaled transversely of said frame is a shaft 14, which is driven by a motor (not shown) or from a suitable source of energy. 85 Mounted upon the shaft 14 are two eccentrics 15, the depending rods 16 of said eccentrics being pivotally connected to a die 17, slidably mounted between the standards 11. The four upper corners of the die are provided with outwardly-extending guide-arms 18, which slidably engage vertically-disposed guide-rods 19, carried by the standards 11. The upper ends of the rods 19 are held by hinge members 20, which are easily disengaged from said rods to permit of the die 17 90 being removed when disconnected from the depending rods 16 of the eccentrics 15.

The area of the die 17 is approximately the same as that of the molds and is adapted to 100 descend into the molds 3, when they are positioned beneath said die. The bottom of the die is formed with a convex surface 21, conforming in curvature to the bed-plates 4, of the molds 3. The convex surface 21 at 105 one end of the die terminates in a bead 22 and at the opposite end in flute or groove 23, the bead and groove forming the interlocking edges of our improved concrete plates or blocks. The bead edge 22 and flute edge 23 110 of the molded block thus come next to the stationary sides 6 of the mold-casing, as

To put our invention into practice, we construct the apparatus whereby the operation 55 of forming plates or blocks can be continuously performed, thus insuring a large out-

shown, and when the die is elevated and the hinged sides 7 opened the block can be removed by suitable implements applied to the solid ends of the blocks. The relatively fragile beaded and fluted edges of the blocks are thus protected during the removing operations. Another advantage of this construction is that the rib-like edges 22 23 of the dies 17, which form the beads and flutes of the blocks, operate close to the inner faces of the stationary sides 6 of the mold-casing, and thus serve as cut-off devices to the material and feed only the required amount into the mold.

15 In Fig. 3 of the drawings we have illustrated, in conjunction with the apparatus, a track 24, located contiguous to the press 9. This track is employed for conveying the finished product to a suitable drying or 20 "curing" compartment (not shown) disclosed in the above-mentioned application.

In forming concrete blocks or plates the mode of procedure is as follows: The mold 3, in front of the press 10, is filled with concrete 25 and moved beneath the die 17 of said press and subjected to a pressure. The mold is then moved forward, refilled, and then moved forward to the press 9, where it is subjected to a final pressure. After the mold has been 30 moved from beneath the press 9 the side walls 7 are lowered and the finished product removed, which in Fig. 8 of the drawings we have designated 25.

During the above operation other molds 35 are being filled, pressed, and refilled, and it is obvious that a plurality of cars, molds, and presses can be economically used in connection with the circular track.

By referring to Fig. 8 it will be observed 40 that the curved plate or block is provided with a grooved or fluted edge 26 and a beaded edge 27. When a plurality of these blocks or plates are assembled to conform to a col-

lar, cylinder, or sleeve, the edge 27 of one block or plate will interlock with edge 26 of 45 its adjoining block or plate, thus providing a non-collapsible structure capable of withstanding considerable external pressure. Where the blocks or plates are used for sewers and conduits, I form some plates or 50 blocks 28 (see Figs. 4 and 5) with openings 29 for manholes, this being accomplished by placing a mold-plate 30 upon the bed-plate of a mold.

What we claim, and desire to secure by 55 Letters Patent, is—

1. In a molding apparatus a press-frame including spaced side members, guide-rods connected at one end to said side members and extending parallel therewith, brackets 60 each having a hinged member adapted to be detachably engaged with the free end of one of said guide-rods, a press-die, guide-arms connected to said die and slidably engaging said guide-rods, a track beneath said press-frame, a plurality of trucks movable upon said track, and a mold carried by each of said trucks and adapted to alternately receive said dies.

2. In a molding apparatus a press-frame 70 including spaced side members guide-rods connected at one end to said side members and extending parallel therewith, brackets each having a hinged member adapted to be detachably engaged with the free end of one 75 of said guide-rods, a press-die, guide-arms connected to said die and slidably engaging said guide-rods, and a mold adapted to be engaged by said die.

In testimony whereof we affix our signatures in the presence of two witnesses.

ALBERT A. PAULY.
DAVID HEINSELMAN.
